UNITED STATES PATENT OFFICE

HARRY E. SIMMONS, OF TOLEDO, OHIO

SHAVING BRUSH

Application filed April 22, 1931. Serial No. 531,932.

This invention relates to devices such as shaving brushes used to lather and/or to work up or evolve a lather or softening agent on the portion of the body to be shaved.

5 The common method of now lathering the face preparatory to shaving is to moisten a regular shaving brush constructed of bristles set in a handle, and then applying shaving cream or shaving soap on the moistened end and rubbing or agitating on the face or in a receptacle to work up a lather to soften the beard.

10 My invention provides for an entirely new method. It is a very inexpensive device that combines both the brush and the softening agent such as soap, etc., into a single unit that can be moistened and used once, and then discarded.

15 For purposes of illustration, but not of limitation, an embodiment of the invention is shown on the accompanying drawing, in which:

20 Figure 1 is a plan view of the first step employed in making the brush in which the strands are looped;

25 Figure 2 shows the next step in the method in which one end of the loop is bound;

30 Figure 3 is a plan view of the next succeeding step in which the opposite end of the loop is cut off or looped to provide the brush end; and

35 Figure 4 is a plan view of the shaving brush in its final form.

One practical method of constructing my invention may be as follows, with the numerals and letters referring to the attached drawing.

40 First many equal loops are made with string, twine, jute or hemp fibers, or fabrics—preferably with jute or hemp fibers of a fine, semi-stiff nature.

45 One end of the looped material is bound about as illustrated by letter (c) of Figure 2. The opposite ends are then clipped off evenly, leaving the many loose ends as illustrated by letter (b) of Figure 3, giving the device a brush-like construction.

50 The bound end of this device may then be dipped in any substance such as glue, varnish, nitro-cellulose, sealing wax, or any other

suitable material that would harden or dry, thus making an efficient handle for the device. This feature is illustrated by letter (d) of Figure 4.

55 The brush end of the device, as illustrated in the drawing by letter (b) of Figures 3, is then impregnated, as shown at (e) in Figure 4, with the shaving lathering, or beard-softening substance, or compound, or any of the many materials used to soften or prepare the beard for shaving. This can be accomplished by either dipping the brush end into a solution of the impregnating material and allowing to dry, or by dusting the material in a dry form into the brush. After 60 the brush has been impregnated with the shaving material it may be placed in a container of cellophane, or other suitable material, to retain the shaving material in place.

65 The device is then completely ready for use. To use it, it is necessary only to moisten the brush end with water and rub or agitate on the face or surface to be shaved.

70 After using once the device may be discarded as the cost is low.

75 Some of the advantages of my invention are as follows:

Many times in traveling the shaving brush and shaving cream are forgotten, and my invention will make a very inexpensive and 80 convenient substitute.

For every-day use my device will be more sanitary and aseptic to use as it could be purchased sealed in a suitable envelope or container, used once and then discarded. It 85 is entirely possible that the regular old-style shaving brush on a shelf could collect dust and harmful bacteria which would then be transmitted to the face by contact.

The inexpensiveness of my invention is 90 also a very practical advantage.

95 The foregoing detailed description has been given for clearness of understanding only, and no unnecessary limitations should be understood therefrom, either in construction methods or in materials used, but the appended claims should be construed as broadly as permissible in view of the prior art.

What I claim as new and desire to secure by Letters Patent is:

1. As a new article of manufacture, a shaving brush having a plurality of folded strands of vegetable matter, means binding the folded ends of said strands, and a dried plastic substance completely enclosing said binding means and the looped ends of the strands providing a casing and handle therefor, and shaving soap impregnating the free ends of the strands, said strands being porous whereby to absorb and retain the shaving soap.

2. As a new article of manufacture, a shaving brush having a plurality of strands of vegetable matter, means binding the strands at one end thereof, and a dried plastic substance completely enclosing said binding means and the adjacent ends of the strands providing a casing and handle therefor, and shaving soap impregnating the free ends of the strands, said strands being porous whereby to absorb and retain the shaving soap.

In testimony whereof I have hereunto signed my name to this specification.

28 HARRY E. SIMMONS.
